UNITED STATES PATENT OFFICE.

SWAN SWANSON, OF HOBART, WASHINGTON.

RAILROAD-GATE.

1,285,460.

Specification of Letters Patent. Patented Nov. 19, 1918.

Application filed December 8, 1917. Serial No. 206,299.

To all whom it may concern:

Be it known that I, SWAN SWANSON, a citizen of Sweden, residing at Hobart, in the county of King and State of Washington, have invented new and useful Improvements in Railroad-Gates, of which the following is the specification.

This invention relates to new and useful improvements in railway gate operating mechanisms and the principal object of the invention is to provide an apparatus operated by the closing of an electric circuit, said circuit being closed by the train coming in contact with a member located adjacent the track.

Another object of the invention is to provide a gate normally held in raised position by gravity and magnetic means for holding said gate in lowered position.

Among other features the invention includes a motor for lowering the gate, magnetic means for holding the gate in lowered position, means for switching the current from the motor to the magnetic means when the gate reaches its lowest position, a member adapted to be operated by the train for completing the circuit, and a second member operated by the train for breaking said circuit to permit the parts to return to their normal position.

Another object of the invention is to provide a device of this character which is simple and durable in construction, reliable and efficient in operation and one which can be manufactured and placed upon the market at a minimum cost.

The invention consists in certain other features of construction and in the combination and arrangement of the several parts, to be hereinafter fully described, illustrated in the accompanying drawings and specifically pointed out in the appended claims.

In describing my invention in detail reference will be had to the accompanying drawings wherein like characters denote like or corresponding parts throughout the several views, and in which:—

Figure 1 is a diagrammatic view of the invention.

Fig. 2 is an enlarged view of the train operated device, the casing therefor being shown in section.

Fig. 3 is a section on line 3—3 of Fig. 2.

Fig. 4 is an enlarged view of the gate operating mechanism.

As shown in these views 2 represents the gate supporting housing and 1 the gate which is pivoted to said housing at 3. The extended lower end of said gate is provided with a receptacle 4 which is adapted to receive cement or other material to form a counter-weight, such material being of greater weight than the long end of the gate so as to hold said gate in raised position. Within the housing is located an electric motor 5 the shaft of which extends through the housing and is provided with a toothed wheel 6, said wheel being so mounted on the shaft as to have free movement in one direction so that the gate may return to its raised position without operating the motor. 7 indicates a semi-circular ratchet member located on the gate with which said toothed wheel engages. 8 indicates an arm carried by the gate and having one end bent at right angles as at 9 and being formed of suitable material to provide an armature for coöperating with the magnet 10 carried by the housing. 11 is a contact plate secured to the housing and connected with the magnet by the wire 12, and 13 is a spring contact carried by the gate and adapted to engage with said plate 11 when the gate is in its lowered position.

14 is a curved contact plate located on the housing and connected with the motor by the wire 15; and 16 is a curved plate carried by the gate and adapted to contact with the plate 14 in the raised position of the gate and to remain in contact with said plate until the gate nears the end of its downward movement. The plate 16 is connected with the spring contact 13 by the wire 17.

The train operating device for completing the electric circuit to the motor consists of a lever 18 pivoted at 19 in a casing 20 located at a suitable point adjacent the track. The

lever is so positioned that its upper end will project a slight distance above the top of the rail where it may be struck by a suitable projection carried by the train. The lower 5 end of the lever is secured to a coil spring 21 by a flexible connection 22, the coil spring being secured to the bottom of the casing, 23 indicates a pair of rollers engaging with the flexible connection 22 and suitably supported within the casing. The lever 18 carries a magnet 24 and a contact 25 which is connected to the magnet by means of the wire 26. The magnet is connected by a wire 27 to a battery 28 and the other pole of this 10 battery 28 is connected by a wire 29 with the plate 16 carried by the gate. 30 indicates an arm pivoted on the pin 19 carried by the casing 20 and said arm is provided with a contact 31 and an armature 32. 33 indicates 15 a spring secured to the casing and engaging with the outer end of said arm. The casing 20 is provided with a rounded top which is closed by a sliding cover 20' having an opening therein through which the upper end of 20 the lever 18 extends. This casing is to be located in a pit below the track and the casing is secured in position by means of a pair of bars 20^x each having one end bent up and secured to the casing and its other end 25 curved upwardly to form a groove to engage the bottom of one of the rails, the other side of the rail being engaged by a strip 20^x secured to the part 20^x. At a convenient point along the track I locate another casing 30 similar to that indicated at 20 and containing a pair of curved contact plates 34 suitably insulated from the casing and having their adjacent ends spaced apart. One of these plates is connected with the contact 31 35 by the wire 35 and the other plate is connected by the wire 36 with the motor and magnet 10 on the gate. Within this casing is also pivoted a lever 37 similar to the lever 18 and provided 40 with the rollers and spring as before. The upper end of this lever projects through the casing and is located close to the rail so as to be struck by a train. 38 indicates a spring contact carried by the lever 37 and 45 adapted to engage with each of the plates 34 and in the normal position of the lever 37 will bridge the space between said plates. 50

As the train approaches the crossing guarded by the gate it will strike the lever 55 18 so as to rock the same on its pivot 19 and the contacts 25 and 31 will come into engagement so as to complete the circuit and thus energize the magnet 24. This will cause the armatures 32 to adhere to the magnet so that after the passage of the train the spring 21 will return the lever 18 to normal position and the arm 30 will be carried with it. Thus the contacts 31 and 25 60 are held in engagement so that the circuit to

the motor will be completed and said motor 65 operated. Thus the gate will be lowered. When the gate reaches its lowest position the contact plate 16 will leave the plate 14 thus breaking the circuit to the motor and at the same time the spring contact 13 will 70 contact with the plate 11 so as to switch the current to the magnet 10. This will cause the armature carried by the part 9 to adhere to the magnet and thus hold the gate in its lowered position. As the train passes 75 the crossing it will come in contact with the lever 37 thus moving the same so as to break the contact between the plates 34 and thus break the circuit. The space between the plates 34 is sufficient to permit the spring 33 80 to return the arm 30 to normal position due to the magnet 24 being deenergized so that when the arm 37 is returned to normal position the circuit is broken by the disengagement of the contacts 25 and 31. The magnet 85 10 being deenergized the gate will be returned to its raised position by the counter weight 4. Thus the plates 16 and 14 will be placed in engagement again ready for the next movement of the operating lever. 90

As shown the device is adapted to be used on a single track railway and it will be understood that a pair of operating levers 18 will be used so that the gate will be operated by a train coming from either 95 direction. Only a single lever 37 is necessary as said lever may be placed adjacent the crossing so that the current will be broken as the train is passing the crossing. It will of course be understood that the device may be adapted for use on double track railways without departing from the spirit of the invention. 100

It is thought from the foregoing description that the advantages and novel features 105 of my invention will be readily apparent.

I desire it to be understood that I may make slight changes in the construction and in the combination and arrangement of the several parts, provided that such changes 110 fall within the scope of the appended claims.

What I claim is:—

1. A device of the class described comprising a gate, means for normally holding the same in open position by gravity, an electric motor for closing said gate, a pivoted lever adapted to be struck by the train, a pivoted arm adjacent said lever, contacts carried by said lever and arm, an electric circuit including said contacts and the motor, 115 an armature carried by the arm, and a magnet carried by the lever and located in the circuit and adapted to engage with the armature when energized to hold the contacts in operative position. 120

2. A device of the class described comprising a gate, a motor for closing the same, a pivoted lever adapted to be struck by the 125

train, a pivoted arm adjacent the lever, contacts carried by said arm and lever, a magnet carried by the lever, an electric circuit including said motor, the contacts and said magnet, 5 an armature on the arm adapted to engage with the magnet to hold the contacts in engagement with each other when the magnet is energized, means for returning the lever to normal position, and means operated by the train for breaking the circuit to permit 10 the arm to be disengaged from the magnet.

In testimony whereof I affix my signature.

SWAN SWANSON.
